UNITED STATES PATENT OFFICE

CLIFFORD E. HARRISON, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

GRATE CONSTRUCTION

Application filed June 3, 1925. Serial No. 34,626.

My invention relates to furnaces and it has particular relation to stokers.

One object of my invention is to provide a plate extension for stokers which shall be of compact and rugged design suitable for inexpensive quantity production methods of manufacture, and which shall comprise parts easily made and readily assembled with a minimum expenditure of time and of money.

10 Another object of my invention is to provide an extension plate with a nose piece which may be renewed when damaged by the action of the furnace without the necessity of disturbing the adjacent portion of the retorts or tuyere stacks.

Other objects and applications of my invention, as well as details of construction and operation, whereby my invention may be practiced, will be apparent more fully hereinafter, when taken in connection with the accompanying description, claims and drawings, wherein

Fig. 1 is a detail view, partially in elevation and partially in section, of the rear end portion of a stoker construction embodying my invention;

Fig. 2 is an enlarged top plan view of the extension plate of Fig. 1;

Fig. 3 is a longitudinal sectional view 30 taken on the line III—III of Fig. 2;

Fig. 4 is a transverse sectional view taken on the line IV—IV of Fig. 2;

Figs. 5 and 6 are top plan and side elevational views, respectively, of the base section 35 of the extension plate;

Fig. 7 is a transverse sectional view taken on the line VII—VII of Fig. 5;

Figs. 8, 9, and 10 are top plan, side and end elevational views, respectively, of the 40 detachable nose piece;

Figs. 11 and 12 are top plan and side elevational views, respectively, of a modification; and

Fig. 13 is a longitudinal sectional view 45 taken on the line XIII—XIII of Fig. 11.

Referring to Fig. 1, a rear end 1 of an underfeed stoker comprises a supporting framework 2 which is mounted on transversely extending beams 3 and 4. The framework 50 2 slidably supports an extension grate 5 actu-

ated by linkage 6 in the usual manner. The framework 2 also includes a pair of spaced walls 7 and 8, the former of which is provided with a damper 9 for controlling the flow of air to extension grates 5 and grate support 2a. 55 Tuyères 11 and extension plates 12, of which only one is shown, may be supplied with air from the main wind box formed by the framework 2. The stoker comprises the usual series of tuyères 11 which alternate with retorts 13 across the width of the stoker. The extension plate 12 shown in the drawing is of the type associated with the retorts 13, serving as a continuation of the floor thereof; but it is not materially different from that 60 associated with the tuyères 11.

The extension plate 12 comprises a horizontal base section 14, a front end 15 of which is provided with depending flanges 16 and 17 which are supported on a member 18 carried by the framework 2. A forward movement of the extension plate 12 is prevented by a plate member 18a which abuts against edge portions 16a and 17a of the flanges 16 and 17, respectively. It is noted that the rear end of the plate member 18a is supported on the member 18, as shown in Fig. 1. The rear end 19 of the base section 14 is provided with a depending wall 20 which extends between side wall flanges 21 and 22. These flanges are respectively provided with outwardly extending grooved portions 23 spaced vertically from the lower edge of the side wall flanges 21 and 22. The grooved side wall portions 23 respectively interlock with adjacent extension plates (not shown) so as to prevent siftings and air leakage therebetween. 75

The lower edge of the wall 20 of the base section 14 is provided with an offset horizontal extension 24, a free edge 25 of which is raised as shown in Fig. 3, for reasons as will presently appear. An under side 26 of the wall extension 24 is provided with spaced lugs 27 which rest on an upper edge 28 of the supporting wall 7 (Fig. 1). A rearward movement of the base section 14 is prevented by lugs 29 which extend downwardly from the under side 26 of the extension 24 so as to engage a side 31 of the supporting wall 7. 95 100

Thus, the base section 14 is locked against forward and backward movements, but it may be readily removed from the supporting framework 2 by lifting it vertically.

As noted above, my invention further contemplates a removable nose piece 32 for the extension plate 12, which may be readily replaced when damaged by the action of the furnace without disturbing the base section 14. Since the renewable nose piece 32 represents approximately one-third of the total weight of the extension plate 12, a considerable saving in material is thus afforded. The renewable nose 32 may take various forms as shown in the drawings. Referring particularly to the structure disclosed in Figs. 1 to 4 and 7 to 10, inclusive, the nose piece 32 comprises an upper horizontal portion 33 which is contiguous to a horizontal portion of the base section 14.

The opposite sides of the horizontal portion 33 of the nose piece 32 are provided with side walls 34 and 35 having outwardly extending grooved portions 36 and 37, respectively. As illustrated in Fig. 2, these grooved portions constitute continuations of the side wall portions 23, 23, respectively. The walls 34 and 35 may rest on the horizontal extension 24 adjacent to the opposite side thereof. A rear side 38 of the nose 32 is curved as shown, and it is provided with a forwardly extending section 39 adapted to engage the underside of the raised end 25 of the extension 24. A pair of spaced locking lugs 40 and 41 (Figs. 3 and 8) are formed to engage the upper side of the raised end 25. A chamber 42, which is formed by the nose 32 and extension 24, is provided with a transversely extending slot 43 in the end portion 38 thereof whereby air entering through spaced apertures 44 and 45 in the depending wall 20 may have an outlet and thereby facilitate the cooling of the extension plate 12.

An upper side 46 (Figs. 3 and 5) of the horizontal extension 24 is provided with end and side ribs 47-48 and 49-51, respectively, forming a recess 52 adapted to receive a locking key 53. The front end 54 of the nose 32 is provided with an aperture 55 through which the key 53 may be inserted into the recess 52. The key 53 may be provided with a head 56 of T-shape, whereby the same may be readily gripped while in the aperture 55 by tongs or other clamping means.

The front end 54 is also provided with a hook portion comprising a depending wall 57 and horizontal flange 58, said wall abutting against the end of an overhung edge portion 59 of the base section 14, and said flange extending beneath the same. Hence, the adjacent ends 54 and 19 of the base section 14 and the nose 32, respectively, are locked against relative vertical movement, while the key 53 serves to prevent a relative longitudinal movement therebetween. The flange 39

and the locking lugs 40 and 41 of the nose 32 in cooperation with the raised end portion 25 of the base section 14 also serve to prevent relative vertical movement when the several parts are in the assembled position shown in Fig. 3. The side rib 49 and end ribs 47 and 48 may serve to support the hook-portion 57-58 of the renewable nose 32 and this support may be supplemented by spaced ribs 60 and 61 which extend between the side rib 49 and the end wall 20, as shown in Fig. 5.

When it is desired to replace a damaged nose piece 32, the key 53 is removed and the nose 32 is then moved rearwardly from the base section 14 until the portions 58 and 39 of the nose are respectively clear of the overhung edge portion 59 and the raised end portion 25 of said base section 14, whereupon said nose piece may be lifted vertically. The reverse operation obtains when the nose piece 32 is replaced.

A renewable nose 32' disclosed in Figs. 11 to 13 is distinguishable from that just described principally in the provision of an inclined upper wall portion 62, an under side 63 of which is provided with a hook portion 64 adapted to extend under a shoulder 65 formed by extending rearwardly a side rib 51' of the base section 14'. The end ribs 47' and 48' may also be extended as shown at 66 and 67, to form a recess 69 for the hook portion 64. The ribs 66 and 67 may be inclined as shown in Fig. 13 so as to parallel the under side 63 of the renewable nose.

When it is desired to remove the nose 32', the key 53 is removed, as in the preceding construction, and said nose 32' is then moved rearwardly a distance sufficient to permit the hook portions 64 and 57'-58' to be moved clear of the adjacent portions 65 and 59 of the base section 14.

While I have shown only two forms of embodiment of my invention, for the purpose of describing the same and illustrating its principles of construction and operation, it is apparent that various changes and modifications may be made therein without departing from the spirit of my invention and I desire, therefore, that only such limitations shall be imposed thereon as are indicated in the appended claim or as are demanded by the prior art.

I claim:

A plate extension for stoker grates comprising longitudinally detachable front and rear sections, the front section having a recess and the rear section an opening in alignment with the recess, a locking pin projecting through the opening and into the recess and preventing longitudinal separation of said sections, and vertically interlocking means on said sections located in spaced relation longitudinally of the sections and respectively at opposite sides of said pin.

CLIFFORD E. HARRISON.
